UNITED STATES PATENT OFFICE.

HENRY A. WISE WOOD, OF NEW YORK, N. Y., ASSIGNOR TO WOOD & NATHAN COMPANY, OF NEW YORK, N. Y., A CORPORATION OF NEW YORK.

INTAGLIO-PRINTING.

1,140,860.

Specification of Letters Patent. Patented May 25, 1915.

Application filed February 8, 1907. Serial No. 356,317.

To all whom it may concern:

Be it known that I, HENRY A. WISE WOOD, a citizen of the United States, residing at New York, in the county of New York and 5 State of New York, have invented a new and useful Improvement in Intaglio-Printing, of which the following is a specification.

Intaglio printing is ordinarily done by 10 means of copper plates which may be in the form of cylinders, or may be flat, or curved to cover a portion of a cylindrical surface. These plates are etched or otherwise provided with intaglio designs in a 15 well-known manner. When the design upon such a plate or shell has to be removed and another substituted, the shell, if of the cylindrical or curved type, has to be turned down in a lathe, repolished and reetched. 20 This may be done repeatedly until its diameter grows so small as to make it useless. At this time it has to be thrown away, and the loss in copper is an important item in 25 operating these printing machines.

As is well known the surface speed of an 30 impression cylinder and its printing surface must be the same. This of course is not possible if the printing cylinder is constantly being reduced in diameter, unless 35 there is no gearing between the two, as is in accordance with the practice in making silk and cotton prints, and also I believe, for wall-paper, or unless there is a resilient connection between them as I have described 40 in my application for patent, Serial No. 349,717, filed Dec. 27, 1906.

It is desirable in many instances that a 45 rigid connection be maintained between the two cylinders, and there are other cases where a resilient connection may not yield far enough to permit the entire thickness 50 of the shell to be used up.

The principal object then of the present 55 invention is to provide a means whereby the shell may be used up more closely than has been the case heretofore, and this I accomplish by providing for keeping the cylindrical surface of the plate or shell at a constant outside diameter or radius of curvature.

This invention is especially adapted for 60 use in rotary machines in which the impression and printing cylinders are geared together to run at a constant ratio, but it is 65 also applicable to those in which a yielding

connection is provided in order to more fully carry out the objects of the same.

In order to provide for preparing curved intaglio printing plates, which term is intended to include printing cylinders or 60 shells, for taking successive imprints, I increase the inside radius of the plate and hold the plate on the printing cylinder or arbor in its expanded state. This may be done by supplying a backing to fill in the space 65 left by increasing the radius which in my preferred form is accomplished by forcing a conical core or arbor into the cylindrical plate or shell, the latter being provided with a conical or tapering passage therethrough. 70

When the invention is carried out in this manner, the copper shell is provided with a longitudinal slit, and this slit is preferably on a line at an angle to the axis of the shell. In other words, it makes an acute angle with 75 the direction of motion of the plate, or with the cleaning blade therefor. The purpose of this latter construction is to provide for permitting the plate to yield to permit its inside diameter to be increased, and the 80 slanting direction of the slit is employed for the purpose of preventing the cleaning blade which is used on intaglio printing surfaces, from dropping into the slit which would be the case if the latter were straight 85 across parallel with the axis. It will be understood, of course, that this latter principle is applicable to the edges of flat or other printing plates.

Reference is to be had to the accompanying drawings, in which,

Figure 1 is a perspective view of a copper intaglio printing plate in the form of a cylindrical shell having a slit therein and illustrating one embodiment of this invention, the position of the cleaning blade also being shown. Fig. 2 is a longitudinal sectional view of such a shell showing it as applied to an arbor and illustrating a means for forcing the two bodies toward each 95 other. Fig. 3 is a side elevation of a printing cylinder having a tapered surface showing another way in which printing plates may be applied thereto in accordance with 100 this invention. Fig. 4 is a transverse section showing another form of the invention.

Referring first to Figs. 1 and 2, the printing plate or member in the form of a copper shell *a* is shown as cut through or slit longitudinally, its inside being bored out on 110

a taper to fit the arbor or core *b* which has a similar taper. The first time the shell is used it has the full diameter, but after it has been once reduced and reëtched it would be too small. This reduction in diameter is compensated for by expanding the shell or plate, and providing means for rigidly backing it up. In the form of the invention illustrated in the first two figures, this is accomplished by forcing the arbor farther into the shell, or the shell farther up on the arbor. In this case the arbor itself backs up the plate in its expanded position. I have shown a convenient means for accomplishing this, consisting of a screw threaded projection *f* on the arbor, and a nut *g* fitting on the same and engaging the plate or shell. This nut can be screwed up to force the arbor and shell together and expand the latter. Obviously after the shell is so expanded it can be turned off, polished, and etched as usual, and it will be seen that the shell can be almost all used up without actually reducing its outside diameter. The slit *c* in the shell or channel between its edges will, of course, gradually widen, and as this invention is adapted for use with intaglio plates and shells, it will be seen that a straight slit parallel with the axis of the armor or core would be a disadvantage, as it would allow the cleaning-blade *d* to drop into it once in each revolution. Accordingly I have provided means for preventing the cleaning-blade from entering the channel in the printing member in this particular form, consisting in making the slit considerably out of parallelism with the blade or with the axis of the shell. In this way the blade will pass over the shell and there will be no position in which it can drop into the channel or silt. It will be seen also that I have provided a method of using substantially the full thickness of the curved plate by expanding its outer curvature to a given circle after each reduction of its thickness, and keeping it up to the printing line by supplying to it proportionate thicknesses of metal or other material.

In the species of the invention shown in Fig. 3, the plate bearing surface of the printing cylinder *b* is given a straight taper from one end to the other and every printing plate *a* is originally made with a corresponding inside taper, its outside surface of course constituting part of a cylinder. Now each time the plate is reduced it is necessary only to push the plate up the taper and lock it in position as by clamps *h* and screws *k*, turn it off, polish, and reëtch it. In this way, depending upon the amount of taper, a plate is first used say at the feeder side of the press, and at each reduction is moved toward the other side.

Fig. 4 shows a straight and concentric cylinder *b* upon which there is a shim or

backing piece *e* tapered circumferentially, which supports a printing plate *a* tapered circumferentially in the other direction. The coöperating eccentrically curved contacting surfaces of the plate and backing piece *e* serve to maintain the printing surface after adjustment, substantially coincident with its position before adjustment. Both the plate and backing piece may be secured to the cylinder in the usual fashion, but when the plate is reduced in thickness the shim may be thrust about to the right thus raising the plate to the proper curvature without altering its position on the cylinder.

While I have illustrated and described several forms in which this invention can be practised, I am aware of the fact that other modifications can be made therein without departing from the spirit of the invention as expressed in the claims. Therefore, I do not wish to be limited to the particular structures shown and described but

What I do claim and desire to secure by Letters Patent is:—

1. A printing member comprising a conical core and a curved intaglio printing plate longitudinally adjustable thereon, whereby the plate may be supported with its inner surface at any desired distance from the axis of the core.

2. A printing member comprising a conical core and a curved intaglio printing plate having an inner conical surface, movably mounted thereon, whereby the distance of the inner surface of the plate from the axis of the core may be varied by changing the position of the plate upon the core.

3. A printing member comprising a conical core, and a cylindrical intaglio printing plate mounted thereon, said plate having a conical or tapering bore therethrough and being longitudinally slit.

4. A printing member comprising a conical core and a cylindrical printing plate mounted thereon, said plate having a conical or tapering bore therethrough and being longitudinally slit on a line at an angle with the axis of the shell.

5. A printing member consisting of a conical or tapering core, a longitudinally slit plate having a cylindrical outer intaglio surface, and a conical or tapering inner surface fitting said core, and means for forcing the plate and core longitudinally with respect to each other to drive the plate up toward the larger end of the core and expand the plate.

6. A printing member, consisting of a conical core having a screw projecting from one end thereof, and an intaglio printing plate having a cylindrical outer surface and a conical or tapering inner surface fitting the core, said plate being longitudinally slit, and a nut engaging said screw-threaded pro-

jection for forcing the plate up on the core to expand the plate.

7. An intaglio printing plate consisting of a cylindrical shell longitudinally slit on 5 a line at an acute angle with its axis, the edges of the plate along the slit being flush, whereby a cleaning blade can be used on it.

8. An intaglio printing surface having substantially meeting edges separated along 10 a line oblique to the direction of movement of the cleaning blade, whereby the cleaning blade will be prevented from entering said separation.

9. An intaglio printing member separated 15 along a line making an acute angle with the direction of motion of the plate or cleaning blade therefor.

10. A printing apparatus comprising a backing or supporting member having a 20 higher surface at one edge than at the other,

and a printing member adjustable thereon toward the higher edge, whereby the printing member may be supported at any desired height.

11. A printing apparatus comprising a 25 backing or supporting member, and a printing member, said two members being relatively adjustable upon each other, the contacting surface of one of the members being higher at one edge than at the other, where- 30 by the printing member may be supported at any desired height.

In testimony whereof I have hereunto set my hand, in the presence of two subscribing witnesses.

H. A. WISE WOOD.
